PROTECTED METAL WATER CONFINING MEANS

Norman Smith, Syracuse, N. Y., assignor to Dryco
Corporation, Syracuse, N. Y., a corporation

Application February 23, 1945, Serial No. 579,338

10 Claims. (Cl. 138—27)

2

This invention relates to improvements in protected metal water confining means of the class such, for example, as metal water pipes, metal water jackets for internal combustion engines and metal valves for water lines, in which water is normally confined without room for expansion in the event of freezing of the water, the general purpose of the invention being to provide such metal water confining means with improved safety means to prevent bursting thereof by internal pressure generated as a consequence of water freezing therein. In metal water confining means of the class described, as water confined therein freezes, an excessive internal pressure is generated which is frequently sufficient to burst the water confining means unless means are provided for relieving such pressure.

A specific purpose of the invention is to provide a metal water confining means of the class set forth having an improved form of vent port sealed by an improved form of metal blowout plug which will not accidentally blow out under water pressures of working range but which will blow out of the port under higher pressure generated as an incident to water freezing in the water-confining means.

Further specific purposes of the invention are to provide an improved article of the class set forth wherein the safety port and plug are so constructed that the plug will be instantly and fully released from and blown out of the port as soon as an unsafe pressure is generated within the article; and to provide a safety sealed article of the class described in which the seal is non-corrosive, can be readily and quickly replaced or renewed after being blown out, and is frictionally held in the sealed port in such manner that a minute movement of the seal in blowout direction will completely release the frictionally engaged surfaces of the port and seal.

Other purposes and advantages of the invention will appear from the following detailed description of illustrative embodiments of the invention shown in the accompanying drawing.

In the drawing:

Figure 1 is a perspective view of a metal gate valve for water lines embodying the invention in a preferred form;

Figure 2 is a detail view showing a portion of the body of the valve of Figure 1 and the safety sealing plug therefor prior to insertion of the plug;

Figure 3 is a sectional view taken horizontally

approximately on the line 3—3 of Figure 1, with the safety plug in place; and

Figures 4, 5 and 6 are views similar to Figures 1, 2 and 3, respectively, and showing a modified form of the invention applied to a metal water pipe element in the form of a T-fitting as illustrated in Figure 4, Figure 6 being a sectional view taken horizontally approximately on the line 6—6 of Figure 4.

In the construction shown in Figures 1 to 3, there is shown a known gate valve 10 for a water conduit or line, said valve having a metal body 11, which body is provided with a safety means embodying the invention. The body of the valve may be a bronze casting, or it may be a die casting made from die casting alloys of the conventional zinc or aluminum base type. The valve body is provided with two frusto-conical vent ports 12 in the wall thereof connecting the water flow passage of said body at opposite sides of the gate with the exterior of the valve. The smaller end of each conoidal port is at the inner end of the port, and the port flares outward at a small angle of taper. In the drawing, the degree of taper has been exaggerated for clarity of illustration of the port and its sealing means. In practice, a very small angle of taper between zero and six degrees is employed, preferably an angle of about one-half of one degree.

The seal for port 12 shown consists of a cylindrical metal plug 13, formed of a metal or metal alloy which is non-corrosive and preferably is not harder than that of which the valve body is formed. In the construction shown, the plug 13 is a brass plug which is softer than the valve body and is deformed slightly at its inner end when driven into the port. The plug 13 has a diameter which is intermediate the major and minor diameters of the conoidal port 12, the length of the plug and its preferred diameter, as shown, being such that the inner end portion of the plug will be slightly compressively deformed and wedged in the port short of the inner end of the port when the plug is driven into the port until its outer end is flush with the exterior of the valve body. A soft brass plug is preferable.

When so driven into the port, as shown in Figure 3, the plug seals the port and is frictionally held against ejection from the port. The area of frictional engagement between the valve body and plug is considerably less, however, than the areas of the conoidal port wall and of the peripheral surface of the plug, and this fact, and the outward flare of the port, insures in-

stantaneous full release and prompt ejection of the plug upon freezing of water in the valve body, although the friction grip is strong enough to hold the plug in place under the usual water pressures. While a plug having a length equal to, or greater than, that of the vent port may be employed, the use of the plug shown and above described is preferred, since the plug does not protrude beyond either face of the ported wall and terminates short of the inner face of said wall. By having the plug terminate short of the inner face of the wall, liability of breakdown of metal from electrolytic action at the joint between the wall and plug at the interior of the wall along which water flows is reduced.

In the construction shown in Figures 4, 5 and 6, another embodiment of the invention is shown. In this construction, there is illustrated a known cast or wrought iron water pipe element 14, in the form of a T-fitting, provided with safety means embodying the invention. The wall of this fitting is provided with a frusto-conical vent port 15 which is tapered from the exterior to the interior of the pipe element, the angle of taper preferably being very small as in the case of the port 12, although this angle has been exaggerated in the drawing in order to show clearly that port 15 and its sealing plug 16 are tapered and frusto-conical.

The plug 16 shown is formed of lead and is non-corrosive and softer than the cast iron pipe element. This lead plug completely fills and seals the port 15 and is frictionally held therein. Due to the shape of the plug and port, the plug will instantly fully release and blow out of the port upon excessive rise of pressure resulting from freezing of water in the pipe element.

The plug 16 is, as shown in Figure 5, formed of shredded lead 16a. To seal port 15 with the shredded lead, the inner end of the port is first closed by a suitable blocking or backing element and the shredded lead is then tamped into the port from the exterior of the pipe element until the port is filled with a solid and coherent lead mass or plug 16.

While plugs of other metals or alloys than those described may be employed, lead and brass plugs are especially advantageous in articles of the class described since they will not rust or corrode, and also are inherently somewhat self-lubricative. Such plugs will, therefore, always blow out before a freezing condition of water confined by the article generates sufficient pressure to burst the article.

Owing to the taper of the port in the metal body, the plug is fully relieved of the frictional holding grip by a very minute outward movement of the plug and is thereby instantly freed for full ejection from the port, a result which would not be attained if the port and plug were cylindrical. Owing to the rust proof and non-corrosive nature of the plug, "freezing" of the plug due to such rusting or corrosion which would require an unpredictable extra effort to eject the plug, which effort would probably exceed that required to burst the container, is also avoided.

It will be evident that the normal water pressure within the protected article exerts on the inner end of the plug a force tending to eject the plug from the port, which force is directly proportional to the water pressure and to the area of the inner end of the port. As stated above, the plug is retained in the port against that force by the frictional resistance between the plug and the port walls. In order that this may be ac-

complished, the diameter of the plug and port should be quite small. This has the further advantage of creating only a small leak should the plug be ejected by an abnormal rise in the internal pressure due to freezing or otherwise. I have found that for normal working pressures up to 100 pounds per square inch, a plug diameter at the inner end of $\frac{1}{8}$ inch is entirely satisfactory.

Although I have thus described my invention in considerable detail in the best form of which I am aware, in accordance with the patent statutes, it will be evident that various changes and modifications may be made by those skilled in the art without departing from the spirit of my invention. Accordingly, I desire to be limited only by the prior art and the scope of the appended claims.

I claim:

1. The combination with a water confining apparatus having a body made of metal of the class in which water is normally confined without room for expansion in the event of freezing of the water, of protecting means for preventing bursting of said apparatus by internal pressure generated as a consequence of water freezing therein, comprising a frusto-conical safety vent port extending from the exterior to the interior of said body, said port being arranged with its smaller end innermost and having a small angle of taper, and a blowout plug of non-corrosive metal which seals and is frictionally held in said port.

2. A protected water confining apparatus as claimed in claim 1, in which the plug is a cylindrical plug driven into said port.

3. A protected water confining apparatus as claimed in claim 1, in which the plug is a cylindrical plug of a diameter intermediate the major and minor diameters of the frusto-conical port and has its inner end portion in driven inter-fitted frictional engagement with the wall of said port, the inner end of the plug being short of the inner end of the port and the outer end of the plug being coincident with the outer end of the port.

4. A protected water confining apparatus as claimed in claim 1, in which the frictionally held plug terminates short of the inner end of said port.

5. A protected water confining apparatus as claimed in claim 1, in which the plug is frusto-conical and entirely fills the port, the length of the plug corresponding to that of the port.

6. The combination with a water confining apparatus having a body made of die casting metal alloy of the class in which water is normally confined without room for expansion in the event of freezing of the water, of protecting means for preventing bursting of said apparatus by internal pressure generated as a consequence of water freezing therein, comprising a frusto-conical vent port in said body tapering from its largest diameter at the outer end of the port toward the inner end of the port at an angle of taper which is between zero and six degrees, and a plug sealing and frictionally held in said port, said plug being formed of a non-corrosive metal softer than said body.

7. A protected water confining apparatus as claimed in claim 6, in which the plug is a brass plug of cylindrical form having a driven fit in said port intermediate the ends of the port.

8. The combination with a water confining ap-

paratus having a body made of iron of the class in which water is normally confined without room for expansion in the event of freezing of the water, of protecting means for preventing bursting of said apparatus by internal pressure generated as a consequence of water freezing therein, comprising a frusto-conical vent port in said body which is tapered from its largest diameter at its outer end toward its inner end at an angle of taper which is between zero and six degrees, and a plug of a softer and non-corrosive metal sealing and frictionally held in said port.

9. A protected water confining apparatus as claimed in claim 8, wherein the port is closed by a frusto-conical lead plug frictionally held in the port.

10. A protected water confining apparatus as claimed in claim 8, wherein the vent port is

plugged with shredded lead tamped into a solid mass in situ.

NORMAN SMITH.
